J. P. CONSTABLE.

PHONOGRAPH.

APPLICATION FILED MAR. 22, 1918.

1,359,966.

Patented Nov. 23, 1920.

UNITED STATES PATENT OFFICE.

JOHN P. CONSTABLE, OF WEST ORANGE, NEW JERSEY, ASSIGNOR TO NEW JERSEY PATENT COMPANY, OF WEST ORANGE, NEW JERSEY, A CORPORATION OF NEW JERSEY.

PHONOGRAPH.

1,359,966.

Specification of Letters Patent. Patented Nov. 23, 1920.

Original application filed June 21, 1915, Serial No. 35,265. Divided and this application filed March 22, 1918. Serial No. 223,899.

To all whom it may concern:

Be it known that I, JOHN P. CONSTABLE, a citizen of the United States, and a resident of Llewellyn Park, West Orange, Essex county, New Jersey, have invented certain new and useful Improvements in Phonographs, of which the following is a description.

This application is a division of my co-pending application Serial No. 35,265, filed June 21, 1915, entitled Phonographs or talking machines which has resulted in Patent No. 1,265,179, dated May 7, 1918.

My invention relates to phonographs and more particularly to phonographs in which the reproducer is caused to move across the record by mechanical feeding means.

The principal object of my invention is to provide improved means for controlling the mechanical feeding means, to render the same operative or inoperative, and for controlling the movement of the reproducer stylus to and from operative position with reference to the record surface.

Other objects of my invention will appear more fully in the following specifications and appended claims.

In order that my invention may be more clearly understood, attention is hereby directed to the accompanying drawing forming part of this specification, and in which:

Figure 1 represents a view partly in elevation and partly in section, showing the preferred embodiment of my invention; and Fig. 2, represents a view in perspective of parts of the device shown in Fig. 1.

Referring to Fig. 1, the reproducer 1 is provided with a floating weight 2 which is connected to the body of the reproducer by a spring connection 3 permitting movement of the floating weight upwardly and downwardly with respect to the body of the reproducer. The floating weight carries a reproducer stylus 4 which may be supported by a lever connected to the diaphragm of the reproducer in the manner shown in U. S. patent to Thomas A. Edison, No. 1,055,621. The stylus 4 is arranged to track a record 5 carried by the mandrel 6 which is rotatably supported upon a bed-plate 7, the latter being carried by brackets 8 secured to the inside of the cabinet 9. A cover 10 is hinged, as shown at 11, to the body portion of the cabinet. The mandrel 6 and the record car-

ried thereby may be rotated by a motor 55 shown at 12. The reproducer is carried in a horizontal position in the traveling carriage 14 which is pivoted at one end to a rod 15 extending throughout the length of the mandrel 6. The other end of the carriage 14 rests upon a straight edge 16. The motor has connected thereto a rotatable feed screw 17 which is engaged by a half nut 18 connected to the traveling carriage in a manner to be more fully described. The end of the traveling carriage which is pivoted to the rod 15 has a substantially vertical portion 19 against the inner surface of which a member 20 is preferably slidably mounted by means of headed screws 21 70 which are secured to the said portion 19 and pass through elongated slots 22 in the member 20. The lower portion of the slide 20 is formed with a rearwardly extending tongue 23 to which the feed nut 18 is connected, as by a flat spring 24. The upper portion of the slide 20 is formed with a rearwardly extending tongue 25 in which is threaded a screw 26 arranged to engage the under side of the floating weight 2 when the reproducer stylus is disengaged from the record. The slide 20 is biased to its lowermost position, preferably by means of a spring 27 secured to the tongue 23 which bears on the underside of the part 19 and tends to hold the slide 20 in such position. For elevating the slide, I preferably provide a member 28 rotatably mounted in a boss 29 extending from the portion 19 of the traveling carriage, the member 28 being formed with a handle or finger-piece 30 arranged at an angle to the body portion thereof for rotating the same. The rear or inner end of the member 28 is provided with a pin or projection 31, the axis of which is parallel to but eccentric with respect to the axis of the member 28. The pin 31 is arranged within a horizontal slot 32 formed on the slide 20 so that upon rotary movement of the member 28, the slide is elevated or depressed, depending upon the direction of movement of the member 28. A screw 33 mounted in the boss 29 and having its inner end arranged within an annular groove 34 in the part 28 holds the latter against longitudinal movement in the said boss. 100

When the slide 20 is in its lowermost position, as shown in Fig. 2, the feed nut 18

is in engagement with the feed screw 17, and the screw 26 is below and out of engagement with the floating weight 2, the stylus 4 resting upon the surface of the record 5. With the parts in this position, the rotation of the feed screw causes the traveling carriage to move along the rod 15 and the straight edge 16, the reproducer moving rectilinearly in a horizontal plane to cause the stylus to traverse the record. When it is desired to stop the feeding movement of the reproducer longitudinally of the record and to disengage the stylus 4 from the record surface, the member 30 is turned in a clockwise direction, viewing the phonograph from the front, so as to cause the elevation of the slide 20. This elevation of the slide causes a disengagement of the nut 18 from the screw 17 and also causes the screw 26 to engage the under side of the floating weight and to elevate the same and lift the stylus out of engagement with the record. The slot 32 is not long enough to permit a complete rotation of the member 30, preferably being of such length that one end thereof will be engaged by the pin 31 after the latter has been moved a very slight distance past its uppermost or dead center position in turning the member 30 to elevate the slide 20. It will be apparent that immediately upon the pin passing its uppermost or dead center position, the spring 27 will act to quickly lower the slide 20 the slight distance necessary to carry the pin 31 to the end of slot 32. The parts will then be yieldingly held or locked in inoperative position by the spring 27 with the pin 31 seated in one end of the slot 32. The carriage 14 and the members carried thereby can now be moved by hand along the record to any desired position. The parts may again be brought back into operative position by turning the part 30 in the opposite direction so as to effect the lowering of the slide 20 to the position shown in Fig. 2.

The sound conveyer employed by me is preferably entirely free from flexible joints. It is provided at its smaller end with a substantially horizontally extending portion 35 which is rotatably mounted upon a horizontal neck of the reproducer. The sound conveyer extends from the portion 35, the axis of which is above the record support and the motor, downwardly past the record support and motor in a substantially vertical direction, as shown at 36, and terminates in a substantially horizontal portion 37 passing under the motor. The mouth of the amplifier is arranged opposite an opening 38 in the front wall of the cabinet. When the cover 10 is closed, as shown in Fig. 1, all of the phonographic mechanism is inclosed within the cabinet. Secured to the bottom of the cabinet adjacent the large or exit end of the sound conveyer is a bracket 39 which is

provided with a vertically extending portion 40 having formed therein a straight vertical slot (not shown) through which passes a horizontal pivot pin 42 which is secured within the horn at the bottom of the outer end thereof. The pivot 42 carries adjacent the outer end thereof a washer 43 which bears against the outside of the portion 40 of the bracket and is held in place on the said pivot by a nut 44. During the travel of the reproducer and the stylus carried thereby across the record surface, the outer or exit portion of the horn is constrained by the pivot 42 and the portion 40 of the bracket 39 to remain in a position substantially opposite the opening 38 in the cabinet. During the said movement of the reproducer, the horn or sound conveyer moves laterally about the horizontal axis of the pivot 42, and inasmuch as the portion 35 of the horn always remains in the same horizontal plane, the pivot 42 and the portion of the horn to which the same is connected also move bodily upwardly and downwardly in the direction of the vertical slot 90 in the portion 40 of bracket 39. A tension spring 45 arranged above the center of gravity of the horn and secured to the bedplate 7 and to the part 37 supports a part of the weight of the horn and facilitates the free movement thereof.

While I have shown the preferred form of my invention, it is to be understood that I am not limited to the particular details shown and described.

Having now described my invention, what I claim as new and desire to protect by Letters Patent is as follows:

1. In a phonograph, the combination of a record support, a reproducer having a stylus, a mounting in which said reproducer is directly supported, a slide on said reproducer mounting, means for producing a relative feeding movement between said reproducer support and said record support, said means comprising a member carried by said slide, and means for shifting said slide to cause said stylus to move away from said record support and to cause said member to move into inoperative position, substantially as described.

2. In a phonograph, the combination of a record support, a reproducer having a stylus, a support for said reproducer, a slide on said reproducer support, means for producing a relative feeding movement between said reproducer support and said record support, said means comprising a member carried by said slide, and means comprising a member pivoted on said reproducer support and having an eccentric connection with said slide so as to effect the shifting of said slide when turned on its pivot to cause said stylus to move away from said record support and to cause said member to 130

move into inoperative position, substantially as described.

3. In a phonograph, the combination of a record support, a sound box having a stylus, a support for said sound box, a device movable relatively to said sound box support, means tending to hold the said device in a given position relative to said sound box support, means for producing a relative feeding movement between said sound box support and said record support, comprising an element carried by said device, and means for shifting said device to another position to thereby cause movement of said stylus and said element to inoperative position, said holding means coacting with said shifting means to lock said device in the latter position, substantially as described.

20 4. In a phonograph, the combination of a record support, a sound box having a stylus and mounted in coöperative relation to said support, a device movable relatively to said sound box and adapted to control the movement of the stylus to and from operative position, means tending to hold said device in a position in which the stylus is in operative position, and means coacting with said holding means to effect the locking of said device in another position in which the stylus is held thereby in inoperative position, substantially as described.

25 5. In a phonograph, the combination of a record support, a sound box having a stylus and mounted in coöperative relation to said support, means for producing a relative feeding movement between the sound box and record support, a device movable to two positions to thereby render said means operative and inoperative, means tending to hold said device in one of said positions, and means coacting with said holding means to effect the locking of the device in the other of said positions, substantially as described.

40 6. In a phonograph, the combination of a record support, a sound box having a stylus and mounted in coöperative relation to said support, means for producing a relative feeding movement between the sound box and record support, a device movable to two positions to thereby render said means operative and inoperative, means tending to hold said device in the position in which the feeding means is rendered operative, and means with which said holding means coacts to yieldingly lock the device in the other position, substantially as described.

45 7. In a phonograph, the combination of a record support, a sound box having a stylus and mounted in coöperative relation to said support, a device movable to two positions in one of which the stylus is held thereby in inoperative position and in the other of which the stylus is in operative position, means constantly tending to hold said

device in one of said positions, and means with which said holding means coacts to effect the locking of said device in the other of said positions, substantially as described.

8. In a phonograph, the combination of a record support, a sound box having a stylus, means for producing a relative feeding movement between said record support and sound box, a device for controlling the feeding means and stylus and movable to two positions, in one of which the feeding means is rendered inoperative and the stylus is held in inoperative position and in the other of which the feeding means is rendered operative and the stylus is in operative position, means constantly tending to hold said device in one of said two positions, and means with which said holding means coacts to effect the locking of said device in the other of said positions, substantially as described.

9. In a phonograph, the combination of a record support, a sound box having a stylus, means for producing a relative feeding movement between said record support and sound box, a device for controlling the feeding means and stylus and movable to two positions, in one of which the feeding means is rendered inoperative and the stylus is held in inoperative position and in the other of which the feeding means is rendered operative and the stylus is in operative position, means constantly tending to hold said device in the position in which the feeding means is rendered operative and the stylus is in operative position, and means with which said holding means coacts to yieldingly lock said device in the other of said two positions, substantially as described.

10. In a phonograph, the combination of a record support, a sound box having a stylus, means for producing a relative feeding movement between said sound box and said record support, a device mounted for movement in one direction to render the feeding means inoperative and to effect movement of the stylus to inoperative position, and movable in the opposite direction to render the feeding means operative and to effect movement of the stylus to operative position, means constantly tending to hold said device at the limit of its movement in one direction, and means with which said holding means coacts to yieldingly lock said device approximately at the limit of its movement in the other direction, substantially as described.

11. In a phonograph, the combination of a record support, a sound box having a stylus, a support for said sound box, a slide provided with a slot and mounted on said sound box support, means for producing a relative feeding movement between said sound box support and said record support, 125

said means comprising an element carried by said slide, a member rotatably mounted on said sound box support, and comprising an eccentric pin engaging said slot, whereby 5. it is adapted to move said slide in one direction to cause said stylus to move away from said record support and to cause said element to move into inoperative position,

and a resilient member opposing said movement of said slide and effective to hold said 10 pin in engagement with one end of said slot and thereby yieldingly lock said slide in a given position, substantially as described.

This specification signed this 18th day of March, 1918.

JOHN P. CONSTABLE.
